UNITED STATES PATENT OFFICE

RALPH G. WHITLOCK, OF LOS ANGELES, CALIFORNIA, ASSIGNOR TO RALPH G. WHITLOCK PATENTS, INC., OF LAS VEGAS, NEVADA, A CORPORATION OF NEVADA

PRINTING PRESS

Application filed June 30, 1925. Serial No. 40,631.

Heretofore numerous attempts have been made to design a machine of this character which would comply with the requirements of the laws governing the use of such a press and especially with respect to prevent its surreptitious or fraudulent use; the principal object of my invention is to provide a relatively simple, compact, and durable machine embodying the requisite functional characteristics aforesaid, in which impressions cannot be made, without being accounted for, and in which false records or readings of meters cannot be hidden, or which cannot be fraudulently adjusted or tampered with even by custodians of the keys to the press, without leaving evidence thereof.

Another object of my invention is to provide in such a press a yieldable platen that will provide an automatic "make ready" and thus produce a distinct impression on matter of varying thickness and uneven surface.

Another object of my invention is to provide concealed and inaccessible printing or stamping type at all points of its movement during the action of making the impression and receding same to initial position, thus rendering it impossible to make an impression with the printing type without registering its movement.

My invention is further characterized by providing automatic means for controlling complete movement of the printing mechanism during the descension and elevation of the printing type so that neither movement can be reversed when started until completed.

A further object of my invention is to provide a means to supply ink to the type of the said press in such a way that great numbers of impressions will be made without manual effort or attention, and for this purpose I have supplied an ink pad attached to and operated by part of the mechanism of the press.

A further object of my invention is to provide in a press of the character stated, a recording meter co-operating with the printing mechanism adapted to successively count and register the total number of impressions made by said printing mechanism, and

a control meter actuated in conjunction with said printing mechanism and simultaneously with said recording meter, said control meter adapted to count off the number of impressions for which the press has been set and which may be reset for a predetermined number of impressions.

My invention has for a further object the provision of means for resetting the control meter for an additional predetermined number of impressions, access to said resetting means being prevented by a door which must be destroyed before the resetting operation may be effected.

With the foregoing and other objects in view which will appear more fully as the description proceeds, my invention resides in the novel combination and arrangement of co-operating elements, claimed and shown in the accompanying drawings forming a part of the present application, and in which—

Fig. 1 is a sectional view of the casing from the right.

Fig. 2 is a sectional view of the machine from the right.

Fig. 3 is a plan view of the machine.

Fig. 4 is an inverted plan view of the mechanism below the base plate.

Fig. 5 is a sectional front view of the machine.

Fig. 6 is a sectional view of the rear section of the machine.

Fig. 7 is a detail elevation of the non-reverse.

Figs. 8 and 9 are diagrammatic fragmentary sectional views of the printing head of my invention illustrating the operation of the inking device thereof.

In all of the above described figures, like numbers designate like parts. The terms right, left, front, back, etc., refer to the various sides of the machine relative to the same being viewed from that portion termed the front.

In Figs. 1, 2, 3, 4, 5, and 6, the part designated 20 is the base plate to which all of the mechanism of the machine is attached. To base plate 20 are secured bearings 21 in which rotates crank shaft 22 to which are connected and which actuates all of the vari-

ous parts of the printing mechanism. Said shaft 22, its connecting parts and its relative position to said parts, is clearly illustrated in Figs. 2, 4 and 6. Base plate 20 is provided with an opening 22—A at the back end directly over said shaft 22 through which the connecting parts pass; rigidly mounted on the shaft 22 is the guard box arm cam 23, this cam operates under roller 24, secured by pin 25 to guard box arm 26, which guard box arm 26 is rockably suspended underneath and to center bearing shaft 27 which is mounted in bearings 28 which are securely fastened to base plate 20. Guard box arm 26 is securely fastened to guard box 29, which is supplied with a cover 30, secured by hinges 31. A fastening 32 is secured to and holds cover 30 in its closed position. Protecting shield 33 is movably secured by pin 34 to said guard box 29, and to shield 33 is attached type ink pad 35.

Attached to crank shaft 22 and actuated thereby is connected printing arm link 37 which is connected by pin 38 to printing arm 39; said printing arm 39 is rockably mounted on center bearing shaft 27; said printing arm 39 is permanently attached to printing member 40 which has mounted on it ink roller 41 by pin 42, which rolls on the face of the aforementioned ink pad 35. Permanently attached to the lower face of the printing member 40 is the type 43 with which to print indicia, the major portion of which type can only be removed from the printing member 40 by partly dismantling the press, it being necessary to remove center bearing shaft 27 and raise printing arm 39 out of guard box 29, which gives access to said type 43. Printing member 40 has permanently attached to it, socket 44, in which is mounted removable dater 45, to the lower end of which is attached interchangeable type 46.

Type protecting shield 33 is operated by the movements of printing member 40, which movements are conveyed to the said shield 33 at the top by a tension spring cap 47 containing tension spring 48, which is held in position by shield tension spring holder 49, which is permanently attached to printing member 40; the movement of the said shield 33 is further actuated on its lower side by contact between ink roller 41 which is attached to printing member 40 and ink pad 35, which is attached to the lower section of the said shield 33. The various parts referred to in the above description are best seen in Figs. 8 and 9. When printing member 40, together with type 43, is in normal position in the press, it is completely surrounded on all four sides by the guard box 29 and is covered on its lower face by protecting shield 33, on top by printing member 40, thus making it impossible to gain access to the type 43 without partially dismantling the press, but per-

mits free use of type 43 in full normal operation of the press.

The shaft 22 has non-rotatably secured to it, ratchet wheel 50, which is alined to engage pawls 51 which are rockably attached to bridge 52, by pin 53, tensioned by spring 54, fastened and adjustably tensioned by screws 55 to noiseless relation with ratchet wheel 50 and said bridge is secured to base plate 20 by screws 56. The parts just recited constitute mechanism allowing continuous movement of shaft 22 in one direction only: the shape and spacing of the ratchet teeth in relation to the shape and location of the engaging ends of the pawls, provide, through the alternate wiping contact of the teeth with the pawls, an automatic positioning of the pawls where either one will always be in position to engage and hold the ratchet upon a reverse movement of the shaft and ratchet wheel; thereby providing a means for automatically operating a ratchet device; eliminating heretofore used tension devices, such as springs, and providing a noiseless operation of the pawls in their contact with the ratchet teeth.

Permanently attached to the left end of crank shaft 22 is the main recording meter bevel gear 57 which engages with and actuates a secondary meter bevel gear 58, which is attached to the lower end of and drives recording meter vertical drive shaft 59, the said shaft 59 being held in position by and passing through bearings 60 which are located in and a part of frame 61; drive shaft 59 has securely fastened to its upper end worm gear 62 which engages and actuates gear wheel 63, said gear wheel 63 being mounted on and actuating the main shaft 64 of the recording meter 65A, main shaft 64 passes through and operates decimal wheels 65, which are enclosed by permanent casing 66, which is fastened to and is a part of the recording meter frame 61, and which is provided with a glass covered port 67 through which the said decimal wheels 65 may be read; said frame 61 together with the casing 66, are mounted on a standard post 68, which is secured by screws 69 to base plate 20; the parts referred to in the foregoing section of this paragraph are best illustrated in Figs. 2 and 6. The assembled parts mentioned in the foregoing section of this paragraph constitute a recording meter 65—A which successively records the number of impressions made by the printing mechanism and is actuated directly from the crank shaft 22 by the main bevel gear 57 on crank shaft 22 which meshes with and actuates secondary bevel gear 58 on vertical shaft 59 and worm gear 62 which engages gear wheel 63 on main shaft 64. This recording meter 65—A records one by one each impression as made and provides an accurate method of determining the

total number of impressions made by the printing mechanism.

On crank shaft 22, located between right hand crank shaft bearing 21 and ratchet wheel 50, is permanently secured to said shaft 22 control meter main bevel gear 70, which meshes with and actuates a secondary bevel gear 71, which is permanently fastened to the lower end of and drives control meter vertical drive shaft 72, which shaft 72 is held in and passes through bearings 73, which are secured to and are a part of control meter frame 74; to the upper end of shaft 72 is securely fastened worm gear 75, which meshes 15 with and actuates gear wheel 76, which is permanently secured on control meter main shaft 77, which passes through and operates decimal wheels of meter 78, and both ends of said shaft 77 pass through and revolve in 20 the control meter frame 74; the frame 74 is secured to and is a part of frame post 79 which sets upon and is secured to base plate 20 by screws 80.

The guard box 29 and the printing member 25 operate downwardly against the yieldable platen 81, which is located in the forward end of base plate 20 and operates in platen plate opening 82; platen stops 83, secured by screws 84 to the lower side of said platen, limit the 30 upward movement thereof, the said stops 83 are provided on their upper surface with noiseless bumpers 85; platen 81 is provided on its upper surface with a yieldable cushion 86, preferably of rubber or similar material, 35 and tensioned by coil spring 87, confined at its upper end by platen cone 88, fastened on the lower side of the center of platen 81, and said spring 87 on its lower end encircles spring stud 89, which is a part of platen spring hanger 90, said hanger 90 is securely fastened by screws 91 to the under side of base plate 20; the said platen 81 being thus constructed with a cushion surface and tensioned by a single centrally located spring 87 provides a universally yieldable platen which automatically 45 adjusts itself to a uniform pressure through the varying thicknesses and irregular surfaces of the matter placed over it, to the type with which the indicia is printed, on 50 the said matter, thus providing a uniform legible indicia.

In base plate 20 is opening 92 through which passes coil spring 93, which tensions upwardly guard box arm 26 and is enclosed 55 on its upper end by riding cap 94, which rests against the said printing arm 39, and the said spring 93 rests on the lower end on top of plate 95 which is securely fastened to platen hanger 90 by screws 96 and by means of 60 bends extends from the under side of base plate 20 down and to a point below the other mechanism, at which point it will engage a lower case 201 hereinafter to be described; provides a shield or guard which effectively 65 prevents access to the vulnerable parts of the

mechanism located to the rear of the said plate or shield 95.

Numbers 97 to 134 inclusive show the various parts of the automatic locking mechanism by which the press is locked against surreptitious or unlawful use and the releasing mechanism of the said locking mechanism, and for the purpose of description, the assembly of the parts to be described in this paragraph are termed the press lock 97. Located underneath base plate 20, and immediately in front of printing arm link 37, which operates on crank shaft 22, is press lock latch 97—A which latch 97—A is rockably secured to lock bearings 98 by pin 99, the said bearings 98 are securely fastened by screws to the under side of base plate 20, and are provided with stops 101 which limit the motion of the said latch 97—A; the said latch 97—A is shown in normal position relative to link 37 in Fig. 2, and in locked position by dotted lines. Latch 97—A is operated by a ratchet arm 102, which is rockably connected at its upper end by pin 103; said ratchet arm 102 is provided in its forward end with a coil 90 tension spring 104, which tensions riding pin 105, said pin 105 rides on the lower face of base plate 20 and together with spring 104 provides the necessary tension to maintain ratchet arm 102 in an operative position; the 95 said ratchet arm 102 is provided at about the center with a tooth 106, which engages at certain points of the operation of the press, lock ratchet trip arm 107, which is set vertically and passes upward and through an 100 opening 108 in base plate 20, and passes through an opening 109 in printing arm 39 and an opening 110 in center bearing shaft 27, said openings 109 and 110 are of sufficient size to allow trip arm 107 to fit snugly with 105 in the same, and in addition arm 107 at the top is notched and threaded as at 111, said notch 111 being part of a circular opening 112 drilled to one side of but within the radius of opening 109 and similarly threaded with 110 notch 111 to engage set screw 113 which is screwed therein to hold the said trip arm 107 in its proper position; the lower end of said trip arm 107 is bent at right angles, forming a pawl 114 to engage the tooth 106 in ratchet 115 arm 102.

Suspended underneath and toward the rear of lock ratchet arm 102, is control meter lock trip lever 115, which is rockably connected to control meter trip connecting arm 116 by 120 pin 117, said arm 116 is loosely connected to operating lever 118, which is located in front of control meter 78, said operating lever 118 is a part of rockable shaft 120 which passes through and has its bearings in sections of 125 both the front and rear parts of control meter frame 74, and permanently secured to shaft 120 is oscillating carriage 119; this oscillating carriage 119 has fastened to it pawl finger 121 by screws 122, said finger 121 rests 130

in a somewhat vertical position and oscillates forward and backward to engage in notches 123 in decimal wheels 78—A, 78—B, 78—C and 78—D. Trip lever 115 is further suspended at the rear by hanger pin 124 in hanger 125, which is secured by screws 126 to the underside of base plate 20. On control meter 78, on the right hand side and secured to the face of and in alignment with decimal wheel 78—D, is reset plunger carriage 127, which is rockably mounted on shaft 77, said carriage 127 has operating within it plunger 128, held under tension by spring 129; this plunger rests upon the face of decimal wheel 78—C, and, as hereinafter described, engages in notch 130 in said wheel 78—C; plunger carriage 127 is provided on top with a bearing 131 containing opening 132; spring 133 is curved at its upward end to engage plunger 128, and its lower end is securely fastened to frame 74; decimal wheel 78—D has on its forward side, two pins 134, which engaging against the edges of frame 74, limit the motion of said wheel 78—D to the distance between said pins, or one decimal point. When control meter decimal wheels 78—A, 78—B, 78—C and 78—D have revolved to the limit of the number of impressions to be recorded, which in the use of four of these wheels as limited by pins 134, would indicate one thousand, slots 123 come into alignment in such a position that the face of finger 121 drops into the said slots 123, thus releasing lever 118, rod 116, trip lever 115, which allows ratchet arm 102 under the tension of spring 104 to drop to and rest upon the lower end of lock ratchet trip arm 107, which arm 107 on its next forward movement engages through its pawl 114 with tooth 106 in arm 102 and forces said arm 102 forward to the limit of its movement, and being engaged with latch 97—A pulls latch 97—A into the locked position against crank shaft 22, making it impossible to operate the machine until the meter has been reset. Side plate 200 has a cavity designed to receive a seal containing device having a positioning ring 138, a retaining ring 136 to position a seal 135; ring 136 is retained by spring 142 tensioned latches 140 engaging in an annulus in ring 36, and provided with releasing dogs 138a which are operated by any proper tool or punch, not shown, designed to puncture the seal 135 and force a cut section of the same between the points 138a. Latches 140 are carried in frame 141. The ring 136 and ring 138 are removable upon the releasing of latches 140 permitting access to lock 145, by means of which the downward count meter 78 may be reset. The lock 145 secured by screws 146 has connected to it shaft 147 riding in bearing plate 148 secured by screws 149. Said bearing plate 148 has another bearing 150 for lever 151, secured by pin 152. One end of lever 151 is shaped

as at 153 to engage cam 154 key related to shaft 147. Unitary movement is controlled by ratchet wheel 155 key related to shaft 147, and engaged by spring pawl 156 secured by screws 157. Shaft 147 has key related to it, 70 cam 158, operating against lever 159 mounted by pin 160 to hanger 161 secured by screws 162, which is secured at 163 to rod 164, which operates thru opening 165 in plate 20 and connected by pin 166 in opening 132 of bearing 131 of plunger carriage 127.

The action of turning the lock 145 and rotating shaft 147 unlocks the locking mechanism of the press and resets control meter 78 to a predetermined number, by the mechanical operation of cam 154 first engaging release lever 153 of lever 151 which by lifting trip lever end 115 raises ratchet arm 102 to a point where the tooth 106 is disengaged from the pawl 114, at which point of movement pin 167 operated by shaft 147 engages stud 168 on the forward end of ratchet arm 102 and by a rotary motion lifts and pushes back to its original unlocked position said arm 102, which being connected to latch 97—A drops the said latch from its engaged or locked position against link 37, thus releasing crank shaft 22 for free operations; said ratchet arm 102 when being moved into locked position is guided past pin 167 by spring guide 169, which is secured by screws 170 to the lower side of plate 95, and said ratchet arm 102 resumes its original position sideways under tension of a pin 171 tensioned by spring 172 in carriage 173, which is securely fastened by screws 174 to the side of base plate 20; the next continuance step evolved from the rotation of shaft 147 by lock 145 is the action of cam 158 on reset lever arm 159 which pulls down reset connecting rod 164 and resetting the meter to the original predetermined number of the movements. When decimal wheel 78—D has been rotated to a point where guide pin 134 rests against the edge of frame 74 and causes said decimal wheel 78—C operating through plunger 128, the plunger carriage 127, to raise plunger carriage 127 and its connections through arm 164, reset lever arm 159, to such a position that its forward end will engage with the cam 158 on shaft 147, thus the operation of rotating shaft 147 reverses the action just described and by pulling down plunger carriage 127 to its original position, automatically resets decimal wheel 78—D to the position of a predetermined number of impressions to be made. Thus the control meter 78 may be set upon completion of a predetermined number of impressions for another predetermined number by adjustment of said meter through the medium of lock 145, access to which is precluded other than to the custodian of the keys thereof who is authorized to break the seal 135 and to reset the control meter 78, at which time a new seal 130

may be substituted for the broken seal when flange 136 is replaced and automatically locked by the described latches 140.

Base plate 20 has on its upper face a guide strip 175, which is continuous on said base plate 20 around the parts of the mechanism which are located on the rear section of the press above the base plate 20, see Fig. 2, and which guide strip 175 fits inside of a lock box 176 which rests snugly upon the top of base plate 20, and completely surrounds and protects the various parts of the press located within it; said lock box 176 has on its lower edge and constructed as a part of it, slotted lugs 177, one on either side, which pass through openings 178 which are provided for the same in base plate 20. On the lower side of base plate 20 the said lugs 177 engage with spring latches 179 riding in guides 180 and held under tension by springs 181; the said latches 179 are released by and connected to arms 182, which are a part of shaft 183 supported by hanger 184, the said shaft 183 is operated by connecting link 185, which through pin 186 and lock arm 187 and lock bolt 188 are operated by lock 189, which is securely fastened to the under side of base plate 20 by screws 190.

The locking mechanism for the boxes is operated through lock 189, which is protected by means identical to the recited means adjacent to lock 145 and comprising a retaining ring 192, with an annulus 195, positioning ring 194, latches 196, dogs 198a and spring 198, frame 192, screws 190, barrel 188, arm 187, pin 186, which connects to and operates lever 183 engaging at 182 with spring 181 tensioned latches 179 in carriage 180 engaging pins 177 protruding thru holes 178 in plate 20, to operate to lock or unlock the box.

Base plate 20 has integral with its lower side a box-like structure 200, which surrounds all the mechanism of the press located beneath the base plate 20 and extending down to a point below any of the said mechanism, and having on its right side toward the rear, the recited opening 22-A for revolving crank shaft 22 through which an actuating means may pass to engage and operate with a rotary motion, by either manual or mechanical power, said shaft 22; designed to fit securely into an opening in the bottom of sides 200 is lock bottom plate 201, which engages at the front end with flange 202, by means of flange socket 203, the other three sides of the plate when placed in position against the sides 200 rest against a continuous guide strip 204, thus preventing surreptitious access, and the said plate 201 is further provided with lugs 205 which are integral with said plate 201 and which are threaded to receive screws 206 which are inserted from the top through openings 207 in base plate 20, thus having their heads 208 above said base plate 20 and situated within the before described lock box

176. The operation of breaking the seal and unlocking and removing lock box 176 further provides access to the heads of the screws 206, which, when removed, allow bottom plate 201 to be removed, providing access to all of the parts of the press located below base plate 20; thus is provided by and in the said lock box 176 an effective means of preventing any person from obtaining access to the parts of the mechanism contained therein during such time as the said lock box 176 may be locked. Lock box 176 is provided with a port 210, through which printing arm 39 passes and operates, and port 211 through which passes and operates guard box arms 26, 75 the said arms 26 and 39 operating the various parts of the printing mechanism as hereinbefore described in the front section of the press, the lock box 176 is further provided with a glass covered port 212 over the recording meter 65-A, through which readings of said meter 65-A may be made, and also a similar glass covered port 213 over the control meter 78.

Over and above and completely surrounding all of the mechanism of base plate 20, including the lock box 176, is outer removable case 214, which has at its front end a platen opening 215, through which matter may be placed in position to receive impressions of the indicia; at a point immediately back of platen 81 is shield guide 216, against which any matter to be printed may rest, and which precludes access to any point beyond said guide 216. Said outer case 214 is provided with a glass covered port 218 directly over port 212, through which readings of the recording meter 65-A may be made, and also a similar glass covered port 219 through which readings of the control meter 78 may be made. 105

What I claim is:

1. In a printing press, in combination, a printing member; type secured thereto; a guard box surrounding the said printing member and the said type; a type shield rockably mounted on and within said guard box; an ink pad secured to said type shield; an ink roller revolvably mounted in said guard box and in contact with said ink pad; a tension spring secured to said printing member and tensioning said type shield; means to actuate said printing member within said guard box to make impressions; means to actuate said guard box to hold said matter before, during and until said impression operation is completed; means to retain in contact with, and remove from the face of said type, said ink pad during said operation; means to operate said type shield to cover said type; means to remove said type shield from over said type during said printing operation. 120

2. In a printing press, in combination a base plate, printing means mounted thereon, matter holding means mounted on said base plate, said holding means forming a guard 130

box for the printing means; a recording meter and a control meter mounted on said base plate, and enclosed by a lock case; a crank shaft mounted under said base plate, and actuating the said printing means, said holding means, said control meter and said recording meter, and enclosed securely within a lower lock case; means to operate the said crank shaft while locked within the said lower lock case; means to operate the guard box outside of and from within the said upper lock case while same is locked; means to operate the printing member outside of and from within the said upper lock case while same is locked to said base plate; means to operate the control meter from outside of and through the lock cases while same are locked to the said base plate; means to lock said lock cases; means to seal said locks in said lock cases.

3. In a printing press, a base plate; printing mechanism mounted on said plate; an upper case to enclose said mechanism; a case below said plate having a detachable bottom; locking lugs secured to the upper case and adapted to project through said plate into the lower case; means mounted on said plate to engage said lugs and lock said upper case to said plate; means projecting through said plate to engage and hold the bottom of the lower case positioned, said means being inaccessible when the upper case is positioned and locked; and means to release the means that engage said locking lugs.

4. In a printing press, in combination, a base plate, a guard box arm mounted thereon, a crank shaft rotatably mounted on the under side of said base plate, a cam mounted on said crank shaft, a roller mounted on the end of said guard box arm; means to tension said guard box arm roller against said crank shaft cam and to raise said guard box arm after each movement of a printing operation, coordinately with the revolutions of said cam.

5. In a printing press of the character described, a base plate; a rockably mounted printing member thereon; a rockably mounted guard member thereon; an inking roller mounted on said printing member; an inking pad to supply ink to the printing member mounted in said guard member and said inking roller adapted to supply and distribute ink on said inking pad at each normal movement of the said rockably mounted printing member and guard member.

6. In a printing press, in combination, a base plate; printing mechanism above and below said plate and secured thereto; a case enclosing the mechanism above said plate, means enclosing the mechanism below said plate, said last means having a removable member; means passing through said base plate to hold said removable member posi-

tioned, said means being inaccessible when said upper case is positioned; and locking means within the lower enclosing means to lock the upper enclosing means to the base plate.

7. In a printing press the combination of: a printing member; type secured thereto; a guard box surrounding the said printing member and said type; a type shield rockably mounted on and within said guard box; means to move said guard box and said printing member coordinately to effect a printing operation; means relating said printing member to said type shield to cause said type shield to rock out of shielding position relative to said printing member when said printing member is moved relative to said guard box to effect a printing impression; means to return said type shield to a shielding position relative to said type when said printing member is returned to its normal position relative to said guard box; and inking means associated with said type shield and operated by movement thereof to ink said type between said impressions.

8. A combination as in claim 7 in which said inking means is mounted on said type shield.

9. A combination as in claim 7 in which said inking means applies ink to said type on said return movement of said printing member to normal position relative to said guard box.

10. A combination as in claim 7 in which said inking means comprises a pad mounted on said type shield and brought into inking relation with said type when said printing member returns to its normal position relative to said guard box.

11. A combination as in claim 7 in which said inking means comprises a pad mounted on said type shield and brought into inking relation with said type when said printing member returns to its normal position relative to said guard box; a roller on said printing member adapted to contact said pad during the movement of said printing member to accomplish a printing impression; and yieldable means operating between said printing member and said type shield to maintain said roller in contact with said pad while said pad is out of contact with said type.

12. In a printing press the combination of: a printing member; type secured thereto; a guard box surrounding the said printing member and said type; a type shield movably mounted on and within said guard box; means to move said guard box and said printing member coordinately to effect a printing operation; means relating said printing member to said type shield to cause said type shield to move out of shielding position relative to said printing member when said printing member is moved relative to said guard box to effect a printing impression; means to

return said type shield to a shielding position relative to said type when said printing member is returned to its normal position relative to said guard box; and inking means 5 associated with said type shield and operated by movement thereof to ink said type between said impressions.

13. A combination as in claim 12 in which said inking means is mounted on said type 10 shield.

14. A combination as in claim 12 in which said inking means comprises a pad mounted on said type shield and brought into presurable engagement with said type during the 15 movement of said printing member relative to said guard box between successive printing impressions.

In witness that I claim the foregoing I have hereunto subscribed my name this 25th 20 day of June, 1925.

RALPH G. WHITLOCK.
